UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

DIAPHRAGM DRIVE.

Application filed July 31, 1923, Serial No. 654,915. Renewed June 4, 1927.

This invention relates to acoustic apparatus and has for an object the reduction of the sound wave transition losses between the driving means and the diaphragm.

5 As pointed out in the application, Serial No. 603,005, filed November 24, 1922, a mechanical transmission system is analogous to an electrical system. The inductance L , the capacity C and the resistance R of the electrical system have their respective counterparts in the mechanical field, namely, mass M for inductance; the reciprocal of the elasticity, $\frac{1}{S}$ for the capacity; and r for the mechanical resistance. The characteristic impedance of a mechanical transmission system having an appreciable amount of elasticity S , as well as mass M per section equals, for small energy dissipations in the transmission system,

$$Z = \sqrt{MS} \sqrt{1 - \left(\frac{f}{f_c}\right)^2}$$

25 which, as will be noted from the equation, is an impedance substantially constant with frequency for frequencies not close to the cut-off frequency. In this equation f is any frequency, and

$$f_c = \frac{1}{\pi} \sqrt{\frac{S}{M}}$$

30 is called the cutoff frequency and is the frequency at which the impedance of the transmission line becomes very high and hence substantially cuts off transmission. The

$$\sqrt{\frac{S}{M}}$$

35 represents the velocity of wave transmission in sections per second, along such a line.

According to the present invention, the impedance of (1) the moving parts of the driving motor, (2) the diaphragm, and (3) the mechanical transmission system connecting the motor and the diaphragm, are so chosen that the transition losses of the transmitted sound waves is small.

40 In case the value of the impedance (1) is substantially equal to that of (2), then the impedance of the mechanical transmission system connecting (1) and (2) should have the same value as (1) and (2). If, on the

other hand, the impedance of (1) is different from that of (2), then the impedance of the drive should taper from the impedance of (1) to that of (2), that is, the following impedance relation should exist:

$$\frac{Z_0}{Z_1} = \frac{Z_1}{Z_2} = \frac{Z_2}{Z_3} \dots = \frac{Z_n-1}{Z_n} = \text{a constant} \quad 60$$

where Z_0 is the characteristic mechanical impedance of the diaphragm and the attachments thereto, Z_1 the impedance of the first section of the mechanical line, Z_2 the impedance of the second section, Z_n-1 the impedance of the last section, and Z_n the impedance of the moving parts of the driving motor. This arrangement will, therefore, function as a mechanical transformer for coupling the two unequal impedances. 65

Another phase of the invention relates to the use of large diaphragms composed of mechanically weak material, such as paper, which forms an efficient coupling with the air, and has for an object to provide a drive, the weight of which is not effectively added to the weight of the diaphragm, which, therefore maintains a mechanical impedance which is small and of the order of that of the surrounding air in which it works. This segregation of the weights of the drive and diaphragm is accomplished by providing an elastic coupling between them whereby they are independently vibratile. The driving means preferably also complies with the requirements previously set forth. 80

45 Referring to the drawings, Fig. 1 is a sectional view on line 1-1, Fig. 2, of the diaphragm and its drive. Fig. 2 is a view in elevation. 85

50 Referring in detail to Fig. 1, the electromagnetic drive 1, may be of the type shown and described in detail in Egerton Patent No. 1,365,898, January 18, 1921. This drive 95 100 comprises a rod 2 which reciprocates in accordance with the electric currents supplied to the electromagnetic drive 1. The rod 2 is connected to the center of a reed 3 shown in the plan view in Fig. 2, and which has three equi-distant laterally extending arms 4. Near the end of each of the arms 4 is suitably fastened a pin 5, each of which is fastened in any suitable manner to the center of a reed 6, each of which has three laterally extending arms 7 similar to arms 4. Each of 105

the arms 7 is suitably fastened, for instance, by means of a pin 8 to a point on the diaphragm 9.

The reeds 3 and 6 may be of any suitable material such as steel, aluminum, or the like.

The diaphragm 9 may be a foot or more in diameter. In the form shown, this diaphragm has its periphery clamped between and supported by the rings 10, 11 fastened by bolts 12 and suitably supported, for instance, in an upright position by the base 13 to which ring 10 is fastened by bolts 14. The ring 10 has supporting arms 15, 16, 17 which terminate near the axis of the ring in a circular member 18 which has bolted thereto (bolts 20) the casing 19 which contains the driving motor 1. The opening in the ring 18 may be closed by the cover 21 which is also fastened by the bolts 20.

20 In assembling the device, the diaphragm with the reeds and pin 2 fastened thereto, is moved into position against ring 10 and then ring 11 is fastened on. The drive 1, carried by casing 19 by means of screws such as 22, 25 is moved into position and pin 2, which is threaded, is fastened to pin 23 of the drive by the lock nuts 24 and 25.

If the impedance of the moving parts of the motor 1 about equals that of the diaphragm 9, the masses of the reeds, the pins and the diaphragm should be such that equal masses are found on opposite sides of the three lines A—A, B—B and C—C in Fig. 1, and the reeds 3, 4, 6 and 7 should have a substantial amount of elasticity such as inherent in thin steel, aluminum, or the like, thereby avoiding transition losses. If the impedance of the moving parts of the motor 1 is different from that of the diaphragm and its attachments, (the pins 8), the mass and elasticity of each section of the drive should be so chosen as to taper the impedance between the motor and the diaphragm as above set forth, i. e., the mass and elasticity should increase from section to section as the terminus (motor or diaphragm) of greater impedance is approached.

While the invention has been described in connection with a telephone receiver, it is 50 equally applicable to a transmitter, phonograph or the like.

What is claimed is:

1. A large direct acting diaphragm, a motor element therefor, and means connected to 55 said motor element for driving substantially all points of said diaphragm in phase, the masses and elasticities, from an impedance standpoint, being separated from the diaphragm.

2. A phonic diaphragm, and a drive therefor which varies along its length in mechanical impedance.

3. The method which comprises progressively varying the mechanical impedance of a drive between a motor and a diaphragm.

4. An acoustic device comprising a diaphragm constituting a portion of a mechanical line and a driving means therefor constituting a second portion of said line, the second portion of the line being divided into a plurality of lines in parallel having a total impedance equal to that of the main line, whereby the diaphragm is driven at a number of points in phase.

5. An acoustic device comprising a diaphragm constituting a portion of a mechanical line and a driving means therefor constituting a second portion of said line, the second portion at the diaphragm consisting of a multiple of parallel branches the number of said branches progressively decreasing from the diaphragm section by section to a single line.

6. An acoustic device comprising a diaphragm constituting a portion of a mechanical line and a driving means therefor constituting a second portion of said line, the second portion at the diaphragm consisting of a multiple of parallel branches, the number of said branches progressively decreasing from the diaphragm section by section to a single line the sum of the impedances of the lines progressively varying from the diaphragm to the single line.

7. An acoustic device comprising a diaphragm constituting a portion of a mechanical line and a driving means therefor constituting a second portion of said line, the driving means progressively varying along its length in mechanical impedance, the effective masses and elasticities being, from an impedance standpoint, separated from the diaphragm.

8. An acoustic device comprising a diaphragm constituting a portion of a mechanical line and a driving means therefor constituting a second portion of said line, the second portion of the line being divided into a multiple of parallel lines of a total impedance equal to that of the main line, the velocity of wave transmission per section throughout each of the lines being substantially constant over the whole range of voice frequencies whereby the diaphragm is driven at a number of points in phase.

In witness whereof, I hereunto subscribe my name this 27 day of July A. D., 1923.

HENRY C. HARRISON.
